(57) **CLAIM**

We claim, the ornamental design for a display screen or portion thereof with graphical user interface for disaster recovery infrastructure, as shown and described.

DESCRIPTION

FIG. 1 is a first image in a sequence of images of a display screen or portion thereof with animated graphical user interface for enterprise disaster recovery infrastructure, showing our new design.

FIG. 2 is a second image thereof;

FIG. 3 is a third image thereof;

FIG. 4 is a fourth image thereof;

FIG. 5 is a fifth image thereof;

FIG. 6 is a sixth image thereof;

FIG. 7 is a seventh image thereof; and,

FIG. 8 is an eighth image thereof.

The dotted broken line showing of a display screen or portion thereof forms no part of the claimed design. The stippled shading showing the world map in FIGS. 1 and 2 forms no part of the claimed design. All other shading in FIGS. 3-8 forms part of the claimed design. The outermost rectangle shown in the figures depicts the bounds of the display screen or portion thereof, and forms no part thereof. All other broken lines show portions of the graphical user interface that form no part of the claim. The appearance of the transitional image sequentially transitions between the images shown in FIGS. 1-8. The process or period in which one image transitions to another forms no part of the claimed design.

1 Claim, 8 Drawing Sheets

FIG. 7

The screenshot shows a software interface for Disaster Recovery Visualization. At the top, there are navigation buttons: a magnifying glass for search, a star for visualization, a back arrow for 'Back to Summary', and a close 'X' button. The title 'Distance Recovery Visualization' is displayed above a table. The table has a header row with columns for 'Name', 'Issues', 'Timestamp', 'Entities', and 'SLA Violations'. Below the header, there are several rows of data, each representing an issue for a VM. The data is as follows:

Name	Issues	Timestamp	Entities	SLA Violations
vm-001	SQL-DB-VM01 has 2 categories with conflict...	12/12/2016 12:00:00AM	SQL-DB-VM01	Cause Resolution
vm-001	SQL-DB-VM01 has 2 categories with conflict...	12/12/2016 12:00:00AM	SQL-DB-VM01	Cause Resolution
vm-001	App1-DBVM3 could not be protected because...	12/12/2016 12:00:00AM	SQL-DB-VM01	Cause Resolution
vm-001	App1-WebVM4 mapped target container...	12/12/2016 12:00:00AM	SQL-DB-VM01	Cause Resolution
vm-001	SQL-DB-VM01 conflicting protection rules	12/12/2016 12:00:00AM	SQL-DB-VM01	Cause Resolution

At the bottom of the interface, there are tabs for 'Tasks', 'Alerts', and 'Snapshots', with 'Alerts' currently selected. There are also buttons for 'John' and 'Dan' on the right side.

FIG. 8
